ESTERIFICATION OF OLEFINS

Henri Martin Guinot, Niort, France; vested in
the Alien Property CustodianApplication January 8, 1941, Serial No. 373,691
In France January 23, 1940

10 Claims. (Cl. 260—460)

In industrial practice, available olefins are mostly accompanied with a material proportion of corresponding saturated hydrocarbons the separation of which for the purpose of isolating the pure olefin presents certain difficulties due to the close proximity of the respective boiling points.

It is therefore advantageous to be able to treat directly such mixtures, in gaseous phase or in liquid phase, in order to esterify olefins contained therein without having preliminarily to separate different components thereof.

It has already been proposed to treat directly such mixtures, particularly propane-propylene fractions obtained by rectification of cracking products from crude petroleum oils, by means of hydrating and esterifying solutions, such as concentrated sulphuric solution, in order to absorb olefins comprised therein. The solutions obtained are then diluted in order to bring about the hydrolysis of alkyl sulphuric acids transitorily formed. The liberated alcohols are finally isolated by suitable means, for example by distillation or extraction by means of solvents.

However, the processes heretofore propounded present many disadvantages, the principal ones residing in the impossibility of bringing about a complete exhaustion in olefins of the mixture of hydrocarbons by the hydrating solution, owing to an inadequate treatment, and in the necessity of putting in highly concentrated sulphuric solutions the recovery of which is costly and involves decreases in the yield of alcohols, the latter being partially destroyed in the course of regeneration.

It is a primary object of this invention to improve the methods heretofore proposed for the esterification of olefins. More particularly the invention relates to a process designed to overcome certain disadvantages of olefin esterification processes and to secure better yields of the desired products.

The process of this invention, substantially consists first in liquefying the mixture of hydrocarbons and then in exhausting the liquefied mixture of its olefinic components in an absolutely methodical manner within a battery of absorption elements. Such battery comprises a number of decantation elements interconnected by means of vertical pipings which allow both the olefinic components to be esterified and the esterifying solution to circulate in a counter-current manner. Such circulation is ensured by means of blowing in an inert gas preliminarily compressed. At the ends of the battery there are gathered, on one part, a liquid constituted by saturated hydrocarbons, practically free from

olefin and employable for any suitable purpose, and, on the other part, an esterifying solution, saturated with olefin alcohol is caused to appear therein by dilution and heating.

5 The intimate contact between the mixture of hydrocarbons and the esterifying solution is ensured in the very course of the upflow by the inert gas; this permits of doing away with various means for intense mechanical stirring which have 10 been employed in the most of prior processes and theretofore considered as absolutely necessary. It was then impossible to foresee that the short contact between the two liquids in a piping system designed for their upflow would have been 15 sufficient for obtaining a rapid action of the esterifying liquid upon the diluted olefin.

The esterifying solution, hydrolysed at the outlet end of the battery for causing the alcohol to appear, is completely exhausted in this compound within a still of any suitable type scavenged from its bottom to its top by a current of hot inert gas. In this manner, the regeneration of the acid by concentration in the hot way is carried out in the absence of any trace of alcohol, whereby inevitable destructions inherent to prior processes are avoided. Thus, the formation 20 of charred products is prevented and the initial effectiveness of esterifying bath is almost infinitely maintained.

25 30 In order to show how the invention may readily be carried into practical effect, the same will now be described with reference to the accompanying drawing which diagrammatically illustrates one embodiment thereof and is not to be construed in a limiting sense.

The single figure of drawing schematically shows an olefin hydrating plant according to the present invention.

35 The absorption portion of this plant comprises 40 a series of decantation elements $D_1, D_2 \dots D_n$, the number of which varies according to the nature of the mixture to be treated, the rate of concentration of hydrated acid and operative conditions selected. These decanters are interconnected by means of suitable pipings which will be described further below. Respectively adjoined to each decanter is a gas exhaust head $G_1, G_2 \dots G_n$. The whole battery operates under a pressure made sufficient to maintain the 45 mixture of hydrocarbons in liquid state at the temperature under consideration.

50 A compressor C permits of bringing to the necessary pressure the inert gas serving to effect the upflow. This gas is stored in a tank B from which it is supplied to emulsion vessels E_1 ,

$E_2 \dots E_n$ by means of a pipe M and pipes $t_1, t_2 \dots t_n$ provided with suitable valves.

A collecting conduit N permits of recovering the gas which has served for the upflow in the different elements, and of directing the same back to the compressor C through the medium of a separator S and pipe 2 .

The liquid mixture of hydrocarbons to be treated and contained in a tank P is introduced through a pipe P_n into one end of the battery, while the esterifying solution, for example an aqueous solution of sulphuric acid supplied from a tank A , is introduced into the other end thereof through a pipe a_1 .

The esterifying solution is met in the emulsion vessel E_1 by the mixture of hydrocarbons which, being already almost exhausted in olefin and constituting the upper layer in the decanter D_2 , arrives at this vessel E_1 through the pipe P_1 . Under the action of the inert gas blown in through the pipe t_1 both liquids, under the form of an emulsion, are forced to flow up into the head G_1 , wherefrom after separation of the gas the mixture flows into the decanter D_1 and is therein divided into two layers. The upper layer constituted by saturated hydrocarbons practically free from olefin flows out of the system through a conduit h . The lower layer of D_1 , constituted by sulphuric acid already comprising a certain proportion of alkyl sulphuric acid, flows through the pipe a_2 into the emulsion vessel E_2 in which it is met by the upper layer from decanter D_n arriving thereat through the pipe P_2 . From the vessel E_2 both liquids are caused by the inert gas to flow up into the head G_2 to be thereafter separated in the decanter D_2 , and so on from element to element.

In the emulsion vessel E_n the esterifying solution, already charged almost at maximum with alkyl sulphuric acid, is encountered by a fresh mixture of hydrocarbons outflowing from the tank F . After flowing up into G_n and decanting in D_n the esterifying solution is finally drawn out of the battery through the pipe e .

The chemical phenomena produced in the battery are pretty complex owing to the fact that two reactions take place therein simultaneously but at different velocities, viz.:

(a) At first, at the contact with olefin a certain proportion of sulphuric acid of the esterifying solution gets fixed under the form of alkyl sulphuric acid. This results in a decrease of the free acidity of the bath and, consequently, in a reduction of the concentration of the latter, the quantity of water having remained without variation.

(b) Simultaneously there is observed partial hydrolysis of alkyl sulphuric acid, reaction which not only liberates sulphuric acid, but also produces consumption of water and, consequently, tends to increase the concentration of esterifying solution.

The velocities of these two parallel reactions depend upon a certain number of factors and, in particular, upon the temperature of the esterifying bath, its degree of concentration and content in alkyl sulphuric acid. One therefore ascertains, from one element to the other in the battery, a variation of the free acidity and of the concentration of the sulphuric acid defined by the ratio:

In order to insure the constancy of this ratio,

which is necessary for obtaining good results, it is expedient to provide on each element of the battery a water supply adjustable at will; such water comes from a tank F and is supplied by pipes $f_1, f_2 \dots f_n$.

At any rate, the pressure of the esterifying solution charged with olefin flowing out of the battery through the pipe e is lowered to the ordinary pressure at O and then heated in a tank H and diluted by water inflowing from a tank I through a pipe 3 , for the purpose of hydrolysing as completely as possible alkyl sulphuric acid comprised therein and liberating alcohol therefrom.

The esterifying solution charged with alcohol is then introduced through a pipe 4 into the upper portion of a still K of baffle plate type or checker pile type travelled from its bottom to its top by a hot inert gas current. The esterifying solution, which falls down from plate to plate towards the bottom of such still, is gradually deprived of alcohol and of a portion of water contained therein, whereafter it flows out through a pipe 5 into a boiler L . The latter is provided with heating means and a stirring device R and a strong current of inert gas is blown thereinto by means of a fan V .

Under the action of said heating and stirring the gas is saturated with steam, whereby the sulphuric solution in the boiler is caused to concentrate. Such concentration may be adjusted to the desired extent by acting upon the intensity of heating and upon the delivery of inert gas in proportion to the esterifying solution supply. In this way there is effected a perfect regeneration of the esterifying reagent which after cooling at T is reintroduced into the tank A by means of a pump U and pipe 6 .

The inert gas charged with steam penetrates through a conduit 7 into the bottom portion of the still K where, as has been seen, it causes the elimination of alcohol contained in the supplied solution. The gases and steam released at the top of the still K are introduced through a conduit 8 into a condenser Q ; at the outlet end 9 of the latter there is gathered hydrated alcohol which may be concentrated in an apparatus of known kind (not shown). The non-condensed gases freed from alcohol and water are then taken up by the intake end of the fan V , reheated at 10 , if desired, and then blown again into the boiler L , thereby accomplishing a complete closed cycle.

The invention is not limited to the particular embodiment above illustrated and described, for modifications may be effected therein without departing from the scope of the invention. For instance, instead of separating alcohol by mere condensation, a washing tower may be employed to extract therein the alcohol from the entraining gas by means of a suitable solvent, as is indicated in the French Patent No. 850,938.

Also, the upflow pipes $r_1, r_2 \dots r_n$ of the battery may be jacketed with a view to enable the regeneration of the temperature of reaction.

It may also be advantageous to make the upflow pipes of unequal length in different elements throughout the battery with a view to compensating, by a suitable time of contact, for variations in the reaction velocity from one point to another in the battery.

Neither will the scope of the invention be departed from by effecting heat recoveries between certain elements of the plant. In particular, there may be utilised hot water from the tank Q or T , or both, for reheating the gas at 10 .

It may also be advantageous to provide in the still K one or more intermediate evaporators to insure reheating of the esterifying solution in the course of its exhaustion in the said still.

Example

It was proposed to manufacture isopropylic alcohol from a liquid mixture constituted by:

	Per cent
Propane	80
Propylene	20

The operation was effected in the plant precedingly described and the operative conditions were as follows:

Esterifying solution: SO_4H_2 at 75%;

Number of elements in the battery: 12;

Temperature in the battery: 40° cent.;

Pressure: 20 kgs./sq. cent.;

Nature and pressure of the inert gas for upflow: nitrogen at 25 kgs./sq. cent.;

Delivery rate of liquid propane-propylene mixture introduced into the battery through F_n : 500 kgs./hour;

Delivery rate of esterifying solution entering into the battery through a_1 : 850 kgs./hour;

Hydrolysis of the esterifying bath leaving the battery: dilution to 50% and heating at 80° cent. for one hour;

Inert gas employed in the phase of concentration-dealcoholization: hydrogen;

Regeneration temperature of the acid in L: 120° cent.;

The following results were obtained:

Amount and purity of propane leaving the battery through n : 400 kgs. of propane containing less than 0.25% propylene;

Amount of isopropylic alcohol gathered from pipe 9: 139 kgs. of pure alcohol;

Yield: 97.5%

Although the above stated example was relevant to the treatment of a propane-propylene mixture, the present invention is in no way limited to the treatment of such mixture and is as well applicable to other homologous products, in particular to butane-butylene mixtures.

According to the present process there may also be treated mixtures comprising saturated and unsaturated hydrocarbons having a different number of carbon atoms, such for example as mixtures containing hydrocarbons having 3 and 4 carbon atoms. The various alcohols formed will be simultaneously eliminated by the gaseous current in the still K and there will be gathered at 9 a mixture of corresponding alcohols which will be separated by ordinary means.

Finally the invention is applicable to mixtures rich in olefins and comprising but some percents of saturated hydrocarbons.

As an inert gas to serve for the operation of the battery, there may be employed hydrogen instead of nitrogen, or else hydrocarbons, saturated or unsaturated, under the only condition that they be gaseous and practically without action upon the hydrating solution within the conditions of temperature and pressure selected, for example methane, ethane, ethylene, etc.

The same remarks also apply to the inert gas employed in the phase of regeneration-dealcoholization, but in this case it will be advantageous to make use of a light gas having the best qualities with regards to heat exchange, for example hydrogen.

What I claim is:

1. In a method for esterifying the olefinic component in a hydrocarbon substance containing saturated and olefinic components by means of an esterifying solution, the steps which comprise admixing said substance in liquid phase with the esterifying solution and the hydrocarbon substance with an ascending jet of inert gas under pressure in a confined zone surrounding said gas jet, to produce an upwardly moving emulsion; collecting said emulsion at a higher level than the original contact point of the solution and substance with the gas jet; causing the resulting emulsion to settle into two layers with simultaneous release of inert gas; and separating the layers.
2. In the art of esterifying the olefinic component in a hydrocarbon substance containing saturated and olefinic components by means of an esterifying solution, the method of gradually charging the esterifying solution with olefinic component from said substance, which comprises admixing the substance in liquid phase and the solution in a plurality of successive stages; contacting the esterifying solution and the hydrocarbon substance with an ascending jet of inert gas under pressure in a confined zone surrounding said gas jet, to produce an upwardly moving emulsion; collecting said emulsion at a higher level than the original contact point of the solution and substance with the gas jet; causing said solution to settle into two layers with simultaneous release of inert gas; separating the layers and forwarding one of the layers to the next following stage and the other layer to the next preceding stage.
3. In the art of esterifying the olefinic component in a hydrocarbon substance containing saturated and olefinic components by means of an esterifying solution, the method which comprises simultaneously contacting the hydrocarbon substance in liquid phase and the esterifying solution with an ascending jet of an inert gas under pressure in a confined zone surrounding said gas jet, to produce an upwardly moving emulsion; collecting said emulsion at a higher level and causing it to settle into two layers with simultaneous release of inert gas; and separating said layers.
4. In the art of esterifying the olefinic component in a hydrocarbon substance containing saturated and olefinic components by means of an esterifying solution, the method which comprises admixing the substance in liquid phase and the solution in a plurality of successive stages; contacting in each stage the esterifying solution from one of the next proximate stages and the hydrocarbon substance from the other next proximate stage simultaneously with an ascending jet of inert gas under pressure in a confined zone surrounding said gas jet, to produce an upwardly moving emulsion; collecting said emulsion at a higher level than the original contact point of the solution and substance with the gas jet and causing it to settle into two layers at said higher level with simultaneous release of gas, one of the layers containing hydrocarbon substance partially deprived of olefinic component while the other layer contains esterifying solution partially charged with olefinic component; separating said layers and causing the hydrocarbon substance layer to flow by gravity down to the first named proximate stage and the esterifying solution layer to flow by gravity down to the second named proximate stage.

5. The method of claim 1, one of the layers containing hydrocarbon substance partially deprived of olefinic component while the other layer contains esterifying solution partially charged with olefinic component, which method further comprises adding water to the second named layer.

6. The method of claim 2, one of the layers in each stage containing hydrocarbon substance partially deprived of olefinic component while the other layer contains esterifying solution partially charged with olefinic component, which method further comprises adding water to the second layer in at least one of the stages.

7. The method of claim 2, further comprising collecting the inert gas evolved in each settling step and recycling said gas to the emulsifying steps.

8. The method of claim 1, the inert gas being selected from the group consisting of nitrogen, hydrogen and gaseous hydrocarbons which are inert towards said esterifying solution under the prevailing conditions.

9. The method of claim 1, the hydrocarbon substance and the esterifying solution being at superatmospheric pressure and the inert gas at a superatmospheric pressure higher than the pressure of the hydrocarbon substance and esterifying solution.

10. The process of claim 2 in which the free acidity of the mixture is maintained substantially constant.

HENRI MARTIN GUINOT.
